UNITED STATES PATENT OFFICE.

ERNST HANING, OF UNION, NEW JERSEY, ASSIGNOR TO ADOLF T. HUSER, OF NORTH BERGEN, NEW JERSEY.

DOUBLE-LIFT JACQUARD-MACHINE.

1,299,461.

Specification of Letters Patent.

Patented Apr. 8, 1919.

Application filed December 7, 1917. Serial No. 206,068.

To all whom it may concern:

Be it known that I, ERNST HANING, a subject of the Emperor of Germany, residing at town of Union, in the county of Hudson and State of New Jersey, have invented certain new and useful Improvements in Double-Lift Jacquard-Machines, of which the following is a specification.

This invention relates to double-lift jacquard machines, *i. e.*, jacquard machines in which each harness cord is controlled by two hooks which so long as the "end" or warp thread to which they appertain, remains called, reciprocate in opposite directions, holding the end raised until it is to be depressed for one or more picks in the fabric. The means connecting each harness cord with its two hooks is usually a cord coupling whose upper end portion is forked so as to be attached to the two hooks and whose lower end carries a hook or the like to which the harness cord is attached. The cord couplings—termed "collets"—besides being subject to wear and therefore requiring constant attention, become twisted and due to this and to one branch of each collet necessarily kinking in slackening when the other is up, serious interference with the necessary perfect freedom of up and down movement of the lifting units prevails; moreover, by twisting and also by stretching, the collets change in length so that the alinement of the ends is disturbed and hence the harnesses cannot be used interchangeably.

The principal object of this invention is to provide a coupling means between each pair of complementary hooks and the corresponding harness cord whereby all these objections will be overcome, and this I accomplish by a novel form of coupling device of the kind in which the principal element is a stiff upright member having means for attachment thereto of the harness cord, or equivalent, and a pair of couplings freely slideable up and down on the hooked lower portions of said hooks.

In the accompanying drawing,

Figure 1 shows a jacquard machine in vertical section provided with the improved coupling means;

Fig. 2 is a side elevation of said coupling means and the lower ends of the corresponding two hooks;

Fig. 3 is a front elevation of what is shown in Fig. 2; and

Figs. 4 and 5 are sectional views on line 4—4 and 5—5 of Figs. 2 and 3.

a is the bottom board, *b* the grid, *c* the knives and *d* the sets of hooks of a double-lift jacquard machine.

Preferably the improved coupling means comprises two members, upper member *A* and lower member *B*.

Upper member *A* is preferably composed of wire, thus being stiff, bent to form upright portions or members *e* of suitable length, laterally bent ends *f* on said portions, a transverse connection *g* between said ends, and eyes *h* (closed in the adaptation illustrated) at the lower ends of said portions, standing side by side. Connection *g* is of a length a trifle exceeding the spacing of the adjoining upright portions *d' d'* of hooks *d*, wherefore, since eyes *h* are close together, members *e e* converge downwardly.

Member *B* is a straight length of wire *i* having its ends formed as eyes *j k* (or equivalent) for coupling, as shown, with the eyes *h* of member *A* and for attachment of the harness cord *l*.

Each coupling device so formed has the bent-off end portions *f* of its members *e* penetrating one of the two complementary hooks *d d'*, so that the device hangs pendent, the coupling it affords at one such part where a laterally bent end *f* occurs being adapted to move up and down with one hook while the other such coupling is perfectly free to slide on the part *d'* of the other hook, the device as a whole being kept to practically a single vertical plane of action at all times. The member *B* penetrates its appropriate hole in the bottom board, being sufficiently long so that its eyes *j k* will not interfere with the same in the rise and fall of the coupling means.

The construction being such, as explained, that when one of a complementary pair of hooks rises and falls the up and down motion of the coupling device occurs with perfect freedom with respect to the other hook and without shifting out of its normal vertical plane; no interference of any character can occur and the alinement of the ends, once effected, remains absolutely constant. Further, no undue space being re-

quired in respect to the form or manner of operation of the device, a greater number of lifting units can be employed than is usual in double-lift jacquard machines. The 5 stiff, straight member B obviously contributes to perfect freedom of movement and also affords increased clearance in the vicinity of the bottom board.

To permit the maximum of crowding together, especially where a large number of 10 lifting units is employed, I preferably twist the eyes h each into a plane oblique to the vertical plane of action of the connection g, as shown in Fig. 5.

15 Having thus fully described my invention, what I claim and desire to secure by Letters Patent is:

1. In combination, with the depending hooked portions of a complementary pair of 20 hooks of a double-lift jacquard machine, a harness cord coupling device including a pair of stiff upright portions, harness cord attaching means at the lower end thereof, 25 said upright portions having their upper ends bent laterally and penetrating said hooked portions, and a transverse rigid con-

nection between the bent-off upper ends of said upright portions.

2. In combination, with the depending hooked portions of a complementary pair of 30 hooks of a double-lift jacquard machine, a harness cord coupling device including a pair of stiff upright portions having their upper ends bent laterally and penetrating said hooked portions, a transverse rigid connection between said ends and harness cord attaching means at the lower end of one of 35 said portions.

3. In combination, with the depending hooked portions of a complementary pair of 40 hooks of a double-lift jacquard machine, a harness cord coupling device including a pair of stiff upright portions having their upper ends bent laterally and penetrating said hooked portions, a transverse rigid connection between said ends and side-by-side 45 eyes at the lower ends of said portions arranged in a plane oblique to the vertical plane of said transverse portion.

In testimony whereof I affix my signature. 50

ERNST HANING.
